Patented Aug. 10, 1920.

UNITED STATES PATENT OFFICE.

ASHTON G. STEVENSON, OF NEW YORK, N. Y., ASSIGNOR TO CHICAGO LINO-TABLER COMPANY, OF CHICAGO, ILLINOIS, A CORPORATION OF ILLINOIS.

RULED PRINTING-FORM.

1,349,536.

Specification of Letters Patent. Patented Aug. 10, 1920.

Application filed May 6, 1918. Serial No. 232,682.

To all whom it may concern:

Be it known that I, ASHTON G. STEVENSON, a citizen of the United States, and a resident of New York, in the county of New York and State of New York, have invented a certain new and useful Improvement in and for Ruled Printing-Forms, of which the following is a specification.

My invention refers to the production of tabular or rule-and-figure matter, and has special reference to improvements in so-called tabular systems whereby type forms made by linotype machines and the like are provided with vertical rules.

Such composition or type forms usually comprise a plurality of linotype slugs, or equivalent rows of monotype slugs, together bearing vertical columns of figures or letters and vertical rules which separate the columns. Vertical rules formed by means of mold matrices involve problems of alignment and continuity thus far not solved in the art of machine composition; and it is customary to form the body of the matter by machinery and to then separately apply the column lines or rules. The difficulty is to apply such separate rules quickly and with the degree of accuracy demanded by the printer's art, and it is especially difficult to first make the type form in the manner required to receive the separate rules and to then accurately and securely fasten the rules thereto.

Three distinct systems have been employed for the purpose: By the first system the rule-receiving grooves are sawed in the type form; in the second, special type and groove forming matrices must be used when tabular matter is required; and in the third, other special matrices are required to make rule retaining projections upon the quad surface of the type form, or rule receiving openings having overhanging side walls. Aside from its expense, the sawing system is objected to because of the frequent mutilation of the type faces and because of the rough edges and metallic dust left by the saw. Under the second system, the formation of grooves or notches of sufficient depth to securely hold the rules can only be accomplished by using special fonts of matrices of greater depth than usual and these are objected to because of their cost and for the reason that tabular forms are

frequently desired in type not readily obtainable in such special matrices. One objection to the bendable lugs of the third system mentioned, goes to the fragile character of the minute rule-holding projections on the type form and the separate operation which must be performed to bend or clench the rule holding projections after the rule is placed on the type form and the most serious objection to the third form involving the production of the rule receiving openings having overhanging side walls goes to the complicated and fragile matrices necessary to produce such holes or openings.

The object of my invention is to provide means whereby linotype forms and even monotype forms may be provided with column rules.

Special objects of my invention are, to provide a tabular system which shall be free from the objectionable features of the present systems; which shall permit all the necessary preparatory work to be done with matrices of simple and usual form; which shall not require any working of the metal after the type form is completed by the linotyping or other machine; and which shall provide and include extremely simple and inexpensive rules of a self-locking character, adapted to be pressed into position and which having been thus positioned shall firmly bind themselves into and on the form as well as bind together the component slugs of the form.

The invention in which I attain these objects will be readily understood on reference to the drawings that form part of this specification, and in which:

Figure 1 is a plan view of a type form embodying my invention;

Fig. 2 is a vertical section of the first slug, or row of slugs, composing the form;

Figs. 3, 4 and 5 are enlarged cross sections of several shapes of my novel rule;

Fig. 6 is a similar view showing the manner in which the fins of the rule are converted into retaining barbs;

Fig. 7 is a side view of a pressure tool or planer that I prefer to use in placing the rules in the form;

Fig. 8 is an end view of the tool;

Fig. 9 is an enlarged view showing the operation of the tool; and

Figs. 10, 11 and 12 and 13 are partial side views of ordinary matrices, to which I shall refer.

In the drawings 1, 2, 3 and 4 represent four slugs belonging to a group of linotype slugs making up a type form of indefinite "vertical" length. My novel self-fastening rules, *a*, *b*, *c*, and *d*, are contained in grooves or notches, *e*, provided therefor in the slugs.

10 These rule-containing grooves are properly aligned by the same methods employed in the alining of type, which methods are well understood by those skilled in the art.

The four slugs may also be taken as four equivalent rows of monotype slugs for my invention is admirably adapted to both linotype and monotype forms of composition. But in working with monotype slugs, I find it best to completely form each rule groove 15 in a single slug. I have not yet found it practicable to employ separate slugs to form any single rule groove or notch. With this exception, the description herewith pertaining to linotype forms holds true as to monotype forms.

In Figs. 1 and 2, I have not adhered to an ordinary column formation of type upon the slugs, that being a matter generally understood. Instead, I have made the illustration as though four slugs had been assembled from different forms, my purpose being to depict the flexibility of the system, *i. e.*, to show that my system is not limited to any particular spacing between the type 30 and the rule-holding grooves or notches. Obviously, a rule groove cannot occupy the space of a type, but, except for this limitation, the rule may be placed as near to or as remote from the type as may be desired.

40 My novel rules are wire-like in form and appearance. I prefer to make them of magnetic metal, steel or iron, but other metals, such as brass, may be used. They are chiefly distinguished from others by their somewhat 45 rectangular form, a rectangular form being departed from to the extent necessary to permit them to be drawn or rolled, and to provide printing edges of the several desired forms. I prefer that in most cases the

50 rules shall have substantially flat parallel sides, 5—5, to fit the sides of the grooves in the slugs; and I provide the sides of the rules with outstanding barb-forming fins, 6. The fins are very thin and sharp edged and 55 extend longitudinally from end to end of the rule. The bottom corners, 7 of the rule are somewhat rounded to facilitate the drawing operation and the insertion of the rules in the grooves. The printing edges

60 may be of any of the usual forms, such, for example, as the hair-line edge, 8, the heavy line-edge 9, and the parallel-line edge, 10. By inverting the rule in the holding notches 65 of the type form the bottom, 11, may also be used as a black-face line or rule, and for

this purpose I prefer, as shown at 7', to taper the lower edges so that the bottom of the rule can best serve as a rule of maximum width. The positions of the several rules and the inversion of one of them (rule 70 6) clearly appear in Fig. 2.

The notches or grooves *e*, which contain the rules, are formed in the upper edges of the slugs, that is the two sides *e'*, and the bottom of each notch are in a solid piece of 75 metal, *i. e.*, the walls are rigid with each other and in this sense are unyielding. The depth of the notches is preferably determined by the usual or ordinary matrices used upon the standard linotype machine, 80 but in any case the notches or grooves are of such depth that the edges of the rules are presented in the impression surface of the form, *i. e.*, in the type face surface thereof, when the bottoms of the rules are seated 85 upon the bottoms of the notches. In every case the sides *e'* of the notches *e*, are of greater depth than the distance between the bottom edge of a rule and its fins 6.

The grooves are of less width than the 90 overall width of the rules. When the slugs of the form have been assembled with the several rule grooves *e*, in alinement, the rules are pressed into the grooves; and thereby the fins 6—6 of each rule in the 95 illustration of my invention shown in the drawings are bent upwardly, forming sharp barbs which slightly enter and strongly engage the sides *e*, of their grooves *e*. This action of the rule fins is clearly depicted in 100 Figs. 6 and 9, and thus positioned the rule cannot easily be dislodged; and, obviously, serves to bind the several type slugs firmly together.

As before stated, I prefer that the rules 105 shall be composed of magnetic metal, and, to simplify the placing of the rules in the grooves of the type form, I preferably employ a magnetized pressure tool or planer *f*. This tool is a permanent magnet and is provided with an edge formed to fit the printing edge of the rule. When the rule is positioned in the groove of the tool it is held there magnetically, and, while thus held may easily be alined with and pressed into 110 the receiving groove of the type form. The action of the tool is depicted in Fig. 9. When the barbs of the rule are once engaged with the form, the tool may be removed 115 without danger of displacing the rule. For convenience, I provide the tool *f*, with three edges *f'*, each having a groove *f''*, formed to fit one of the illustrated rule shapes. The tool need not be large, in fact it is so small 120 that it may be carried in the printer's pocket. The flat sides or edges *f'* of the tool which are opposed to the rule receiving grooves are adapted to receive the blows of a mallet in the operation of forcing the 125 rules down into the slots or grooves of the 130

form in the operation known in the art as "planing".

It should be understood that the drawings show the parts greatly exaggerated in size. 5 A correct idea of the proportions may be gained from the following: The surfaces 12 are the quad-height surfaces of the type form. The type 13 with their pedestals 14 rise to a height of substantially forty-three thousandths of an inch above this quad-surface 12. Seventeen thousandths of an inch is usually consumed in the sink of the type, leaving the vertical shoulders, 14', of the type with a height of twenty-six thousandths of an inch. The wire-like rules preferably have a total height of forty-one thousandths of an inch. The fins, 6, 6 of the rule are about four thousandths of an inch in width, measured perpendicularly from 20 the sides of the rule and they are about three thousandths thick at the base and they taper to a feather edge. The matrix-formed grooves *e*, that receive the rules, are slightly wider than the rules, by two or three thousandths of an inch, to rather easily admit the rule fins. The depth of the grooves corresponds to the depth of the rule, preferably forty-one thousandths of an inch.

The grooves and rules may be fully forty-three thousandths of an inch deep; that is, of full type height, measured from the quad surface to the impression surface of the form. But I recommend the height of forty-one thousandths of an inch for the rules and I find that greater accuracy is insured by making the grooves or notches by means of routed matrices provided for the purpose. The mold surfaces of blank or quad forming matrices are not always accurate. Nevertheless, my invention comprehends the employment of quad matrices of proper width for the making of the rule grooves; and also comprehends the employment of rules of full type height. It should be understood that the quad height which is the height produced by ordinary blank matrices such as shown at Fig. 10, provide the form with a level top surface indicated by the dotted line 12, Fig. 2, and upon which 45 surface I prefer to support my rules. This surface as explained is produced at a depth of substantially forty three thousandths below and parallel with the printing or impression surface of the form, when the form 50 is composed of slugs produced with standard matrices on the ordinary or usual linotype machine. And I find that the slight variation in this surface which results from inaccuracies in matrices or alinement is just sufficient to compensate for a height of rule of forty-one thousandths instead of the full type height of forty-three thousandths.

For greater clearness, I have shown in Figs. 10, 11, 12 and 13 the mold edges of 55 the several forms of matrices involved in

the making of the illustrated type form. These matrices are shown of substantially actual size. Fig. 10 depicts a quad forming or blank matrix characterized by a straight edge 15, the dotted lines showing the relative positions of the walls of the co-acting mold cell. Fig. 11 depicts the edge of a type molding matrix, characterized by the standard routing 16 and the type sink 17. Fig. 12 depicts a similar matrix having a blank mold notch or routing, which it is best to employ in making blank pedestals, such as the pedestals, 18, required to form the side walls of the rule groove when the groove is removed from the shoulders of type. In Fig. 13 I have depicted a standard matrix having a shallow routing 19 which may be used in forming the rule grooves. As before stated I prefer to use the matrices of the kind shown in Fig. 10 for forming the rule grooves as these are standard as to outline and it is only necessary to provide such matrices of the proper thickness to make the grooves of the right width to receive and retain the rules.

In Fig. 4 of the drawing, by means of the dotted line 20, I have attempted to show the shellac, or other adhesive substance, with which I coat all my rules. This coating prevents the deterioration of the surface of the rule, and, particularly, prevents rusting, in the case of rules made of annealed steel or iron. The coating is very thin and does not interfere with the use of the printing edge of the rule. A further function of the coating is to assist the barbs in firmly uniting the rule with the walls of the rule groove in the type form and in some instances may effect the fastening of the rule without the engagement of the barbs. It will now be clear that upon the assembling of the type slugs my novel rules may be quickly pressed into place, and that the same are self-secured, without resort to any further operation upon the metal of the type form.

I claim:

1. As a new article of manufacture, a type-form rule for application upon the level top surfaces of type-forms, comprising a straight wire-like piece of metal, in cross section substantially as wide as it is high, and tapering at its top to a printing edge, its sides provided with thin knife-like, type-form-penetrating edges.

2. As a new article of manufacture, a type-form rule for application upon the level top surfaces of type-forms, comprising a straight wire-like piece of metal, substantially as wide as it is high and tapering at its top to a printing edge, being of a height from printing edge to base approximating .043", its sides provided with thin, knife-like type-form-penetrating edges.

3. A tabular type-form, provided with a

- 4
- rule receiving slot having substantially parallel, vertical, rigid and relatively immovable side walls, and a type-form printing rule adapted to be applied to the form by being forced downwardly into said slot, and having type-form thin fins or edges adapted to cut into the metal of the form when the rule is applied thereto and prevent the free removal of the rule.
10. 4. A tabular type form, comprising a type slug containing a groove of a depth not exceeding type height, in combination with a metal rule having its printing edge in the impression plane of the form and having bendable fins adapted to yield as the rule is placed in position in the groove and be inserted in the walls of the groove to hold the rule in place.
5. A tabular type-form having a level top surface and rule receiving slots extending from the printing surface to said level top surface, in combination with type form rules adapted to be applied to the form by being pushed downwardly into said slots upon said level top surface, said type-form rules having type-form penetrating edges which by reason of the rules being applied to the form penetrate the form and prevent the free removal thereof.
20. 6. A tabular type form provided with a groove for receiving a printing rule, the side walls of the groove being substantially parallel, vertical and relatively immovable, in combination with a rule in said groove, the rule being formed wider than the groove and having parts adapted to yield to permit the insertion of the rule in the groove and adapted to engage the walls of the groove to prevent the withdrawal of the rule from
25. 7. A tabular type form provided with a groove for receiving a printing rule, the walls of the groove being substantially parallel, vertical and relatively unyielding, in combination with a rule in said groove, the rule having relatively thin bendable edges adapted to be bent as the rule is applied to the form and adapted to be embedded in the body of the form to prevent the easy withdrawal of the rule.
30. 8. A tubular type form provided with a groove for receiving a printing rule, the walls of the groove being substantially vertical, parallel and relatively immovable, and a printing rule in the groove, the rule having parts which are adapted to be bent as the rule is forced into place.
35. 9. The combination with a printing form composed of linotype slugs which have a level top surface substantially .043" below the face of the printing form, of type form rules adapted to be supported on said surface and provided with bendable fins adapted to be bent as the rule is applied to the form and adapted to engage the metal of the form to prevent the easy removal of the rules from the form.
40. 10. A type form rule for use upon a type form made up of linotype slugs which have a level top surface substantially .043" below the printing face thereof, said rule being of a height substantially the same as from the printing face to said level top surface and having bendable fins for engagement with the metal of the form for retaining the rule on the form.

In witness whereof I hereunto subscribe my name this 20th day of April, 1918.

ASHTON G. STEVENSON.
